Application February 8, 1951, Serial No. 209,949

1 Claim. (Cl. 273—102.1)

1

This invention relates to small-arms or rifle targets which automatically indicate the points hit by the bullets.

Such targets of constructions hitherto known have had some disadvantages, for example the correct functioning of the moving parts has been impaired by lead particles from the bullets, the desired separation of the central area into numerous parts was not possible, and the indicators were visible only for periods which were much too short.

One object of the present invention is to provide an improved automatically-indicating target, and further objects appear from the description below.

According to the present invention an automatically-indicating target of the kind comprising a plurality of co-axial steel rings lying behind one another and retained on partly-spherical supports by spring-loaded rods, the bull's eye being formed by a ring on a slidable tube through the middle of which a slidable rod extends, the tube and rod being provided with means for causing the appropriate indicators to appear above or at the side, the indicators remaining in their indicating positions partly by over-balancing and partly by detent means, and being returned to their original positions by means actuated from the marksman's position, is characterised in that said co-axial rings have seats which facilitate the escape of lead particles and permit said co-axial rings to move bodily rearwards from said partly-spherical supports.

A target according to the invention is shown by way of example in the accompanying drawings,

Figure 1 being a sectional elevation of the target,

Figure 2 a rear elevation,

Figures 3, 4 and 5 details,

Figure 6 a plan corresponding to Figure 5, and Figure 7 the swinging bearing arrangement.

Referring to the said drawings, the target comprises a bullet-stop and guide plate 1 supporting a hollow shaft 2 onto which are slid bored partly-spherical supports 3 spaced from each other by spacing sleeves 4. On each support 3 is mounted a steel ring 5 with a complementary partly-spherical seating centrally disposed. The rings 5 project a short distance in front of the supports 3 (Figure 3). This ensures that the lead particles are deflected forwards and do not usually enter the partly-spherical seatings of the rings 5. If any particles of lead should enter these seatings they soon work their way out forwards or backwards as each of the rings 5 has

a central aperture having a seating zone complementary to and accommodating one of said part-spherical supports 3 (see Figure 3) and a rear escape zone which widens conically rearwards and permits the rearward escape of lead particles from said seating zone. The widest part of the seating zone is at its front so that the ring 5 can move bodily rearwards from the support 3. Moreover, lead particles from bullet impacts are to some extent kept out of the seating zone as shown diagrammatically in Figure 3, in which arrow *a* indicates the path of the arriving bullet, and arrows *b* and *c* the directions in which the lead particles are deflected, and arrow *d* the path of particles deflected by a groove 1. Particles are similarly deflected by the other rings and the sleeve 8 forming the outer bull's eye. The sleeve 8 has a bore through which extends a rod 9 of which the end is enlarged and brought to a point 10. This rod 9 actuates an indicator 24 as described below for the middle of the bull's eye and the point 10 serves to facilitate arranging a card-board target concentrically with the rings 5. The sleeve 8 is arranged on a hollow shaft 11 carrying a ring 13 with a groove 12. Into the groove 12 projects a lever 15 movable about a bolt 14. Upon a bullet striking the sleeve 8 the upper end of the lever 15 strikes a stem 16 on an indicator 17 (see Figure 1, 5 and 6) which is moved upwardly so that its arm 18 is held vertical behind a spring 19. The edge of lever 15 strikes the inclined surface of stem 16 so that indicator 17, which is balanced by arm 42, swings round pivot 21. The tube 11 is moved forwards to its initial position by a compression spring 20. A hit upon the bull's eye centre is indicated by a spring-loaded indicator 24 pivoted on a bolt 26 and actuated from the rod 9. On the rod 9 is a finger 22 (Figure 4) with a catch 23 to engage a hook 25 and so hold the indicator 24 which is loaded by a torsion spring 27 of which one end 28 is held down by a catch 29 of the counter-push member 30 (Figure 1). If the rod 9 is pushed back by the impact of a bullet the hook 25 is released from the catch 23 and the indicator 24 flies up into its indicating position. The rod 9 is returned to its initial position by a compression spring 31. The indicators 32, which indicate the value and position of bullet hits, are swung up in known manner by cam elements 33 on slidable rods 33 arranged behind the rings 5. The rods 33 are pressed against the rings 5 by compression springs 34 so that the rings 5 are held centrally on their supports 3. In Figure 1

only one rod 33 is shown for the sake of clarity in the drawing, but in practice three or four rods engage each ring 5. This arrangement permits the rings 5 to tilt and also to make short rearward movements bodily, thereby facilitating the escape of lead particles from the seatings, and this is of the greatest importance for trouble-free operation of the device. The indicators 17, 24 and 32 having been brought into their indicating positions, they remain there and a pulley 35 is rotated and causes push rods 36 and pairs of forks 37 (Figures 1 and 2) to return the indicators to their initial positions as follows:

Upon actuation of the rope 38 (Figures 1 and 2) the pairs of forks 37 move outwards in known manner in opposite directions and swing the indicators 32 back until they rest against the appropriate cam elements 39 (Figure 2). The upper fork 37 is connected to a bearer 40 (Figure 5) in which is a pin 41 which during upward motion acts against an arm 42 and thus swings the arm 18 clear of the spring 19 so that indicator 17 falls to its hidden position. The upper counter-push member 30 with its catch 29 is raised and reduces the tension of the torsion spring 27 (Figure 4) then the indicator 24 falls and is again held by the finger 22. By the reverse movement of the pulley 35 the torsion spring 27 is again stressed. The indicator 24 is then ready to function again.

Each of the indicators 32 is pivoted on a shaft 44, and so that the bearing 43 (Figure 7) of the indicator 32 does not act over its full length on the shaft 44 either the middle bearing surface in the part 43 is cut out or the shaft 44 is shaped to provide short bearing surfaces.

What we claim is:

In an automatically-indicating target of the kind having a hollow shaft, a series of mutually-spaced part-spherical supports on said shaft, a plurality of co-axial rings arranged one behind another and one on each of said part-spherical supports, and resiliently-loaded rods each having an end pushing against the rear surface of one of said rings and acting to swing a pivoted indicator into view when a bullet strikes the ring, the provision in at least one of said co-axial rings of a central aperture having a seating zone complementary to and accommodating one of said part-spherical supports and a rear escape zone which widens conically rearwards and permits the rearward escape of lead particles from said seating zone, the widest part of said seating zone being at its front so that said ring can move bodily rearwards from said part-spherical support and thereby further facilitate the escape of lead particles from said seating zone.
